(57) **CLAIM**

I claim, the ornamental design for a clasp retainer, as shown and described.

DESCRIPTION

FIG. 1 is a front elevation view of a clasp retainer, showing my new design;

FIG. 2 is a rear elevation view thereof;

FIG. 3 is a side elevation view thereof;

FIG. 4 is an opposite side elevation view thereof;

FIG. 5 is a top plan view thereof;

FIG. 6 is a bottom plan view thereof; and,

FIG. 7 is a perspective view thereof.

Portions in broken lines show environment and form no part of the claimed design.
